United States Patent

Des. 240,568
Patented July 13, 1976

240,568

PURSE GUARD

Robert Grant Ammons, Sr., 1533 Northwick Road,
Baltimore, Md. 21218

Filed Oct. 8, 1974, Ser. No. 513,122

Term of patent 14 years

Int. Cl. D3—99

U.S. Cl. D87—2 R

FIG. 1

FIG. 2

FIG. 3

FIG. 4

FIG. 1 is a front elevational view of a purse guard showing my new design as it would appear in a secured position on a purse handle;

FIG. 2 is a right side elevational view thereof;

FIG. 3 is an enlarged scale perspective view of one side of the purse guard in an open condition; and

FIG. 4 is a perspective view of the opposite side thereof.

1 claim:

The ornamental design for a purse guard, substantially as shown and described.
